Walter Owen. Att'y.

UNITED STATES PATENT OFFICE.

RUDOLPH F. STEHLIK, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed September 3, 1925. Serial No. 54,182.

The present invention relates in general to automatic telephone systems, but relates particularly to improvements in the type of switches commonly known to the art as rotary connectors.

As is well known rotary connectors are extensively used in setting up of connections over one of a number of trunks between a main and private branch exchange, the 10 branch exchange called being usually only provided with a single directory number the same as any subscriber's line. The ordinary two directional type of rotary connector responds to two digits transmitted to it, the 15 first digit positioning the wipers opposite the level of bank contacts in which the desired group of trunks is located, while the second digit positions the wipers on the first bank contact of the desired group. The 20 switch then automatically rotates its wipers until they engage contacts with which an idle trunk is associated. If all trunks are busy the switch continues to rotate until it arrives at the last bank contact of the group 25 and then transmits the busy tone to the calling subscriber.

The ordinary two directional type of switch has access to ten levels, each comprising ten contact sets and, therefore, this arrangement works very nicely where the 10 trunk groups are made up of ten or less trunks. In cases where private branch exchanges are of such capacity that ten trunks are insufficient to take care of the traffic the 15 branch exchange is given two directory numbers. This is objectionable in that if a subscriber desires to connect with the branch exchange it may be necessary to dial both directory numbers owing to the fact that the 20 first group of trunk lines by way of which the subscriber attempted to attain access to the private branch exchange was busy.

In a Wicks Patent No. 1,603,929, patented October 19, 1926, this objectionable feature 25 was overcome by adding vertical test equipment and by modifying the rotary connector circuits so that when groups of over ten trunks were desired the switch was arranged to move its wipers from the level to which 30 they were operated directly to the next

level in case all trunks in the first level were busy. The present invention, however, overcomes the objectionable feature by merely switching from one set of wipers to another, which method in some installations 55 has proved the more desirable.

The present invention also enables the assignment of highly desirable directory numbers to large branch exchanges using more than ten trunks. In the connectors formerly 60 used, as previously stated, the connector switches operate responsive to two digits, the first digit being utilized to elevate the wipers to particular level and the second digit being utilized to position the wipers into engagement with the contacts of the first trunk 65 of a desired group. In the present disclosure in calling trunk groups comprising less than ten trunks, the operation is the same as formerly. If, however, the trunk group exceeds 70 ten, the last digit may be selected to suit the whim of the private branch exchange subscriber, as this digit is not necessary and is absorbed.

The accompanying drawing shows sufficient 75 of a telephone system to enable the invention to be intelligently described. More specifically the drawing discloses a connector of the well known vertical and rotary type with the circuits modified in accordance with 80 the invention. The shaft (not shown) carrying the usual wipers is, of course, also elongated to provide the necessary space for the added wipers which are necessary to the carrying out of the invention. 85

In order that a thorough understanding 90 of the invention may be had, a description will first be given of the manner in which the connections are set up from the calling station to a private line and to a private branch 95 exchange trunk line terminating in a group comprising less than ten trunk lines, respectively, after which it will be explained how any one of twenty trunks may be selected.

The usual subscriber's substation, individual line switch and selector switches used by a subscriber in completing a connection being well understood by those skilled in the art and since this equipment forms no part 100

of the invention, it is believed it will suffice to say that the calling subscriber upon removing the receiver from the switchhook causes his line switch to extend the calling line conductors into connection with an idle selector. The subscriber then operates his calling device in the usual manner causing his line to be extended to a second selector or to a connector such as the connector E, 10 depending on the capacity of the system.

Let us assume that the calling subscriber has set up the connection as far as the last selector and that the wipers of that selector have come to rest on the bank contacts, 15 which are connected to conductors 23, 24, and 25, resulting in the switching relay of the selector completing an energizing circuit for the line relay 26 of the connector E. The line relay 26 upon energizing in 20 turn causes the energization of slow release relay 28. Relay 28, in operating at its armature 39 supplies ground to the release trunk conductor 24 to maintain the previously operated switches operated in the 25 usual and well understood manner. Relay 28 at its armature 38 prepares holding circuits for various relays as will be explained hereinafter and at armature 37 prepares a circuit for vertical magnet 40 and slow release relay 29.

We will first assume that the last two digits of the desired subscriber's number are 1 and 9, respectively. The subscriber, therefore, dials the digit 1 causing line relay 26 35 to drop back momentarily to transmit an impulse by way of its grounded armature and resting contact, armature 37 and its working contact, off normal spring 88 and its resting contact and the winding of relay 40 29 and vertical magnet 40 to battery. The vertical magnet functions in the usual manner to elevate the wipers 74 to 81, inclusive, a number of steps corresponding to the number of impulses transmitted to the line relay 26, which in the present case was 1, and causes the operation of the off normal springs 87 and 88.

Shortly following the transmission of the impulse to vertical magnet 40, slow release 50 relay 29 restores and at its armature and back contact prepares an operating circuit for slow release relays 33, 34, and the rotary magnet 42. Responsive to the dialling of the digit 9, the line relay 26 causes nine 55 impulses to be transmitted from its grounded armature and back contact, armature 37 and its working contact, springs controlled by off normal spring 88, armature of relay 29 and its back contact, back contact and armature 48, the windings of relay 33 in 60 multiple to point 100, where the circuit divides, one branch extending by way of the back contact and armature 53 to the winding of slow relay 34 and battery; the other 65 branch extending by way of armature 62

and its resting contact and the rotary magnet 42 to battery.

Relays 33 and 34 are slow to release and, therefore, although the circuit of relay 34 is transferred, upon the energization of relay 33, from that just traced so that it obtains ground direct from armature 53 and the working contact of relay 33, this relay does not deenergize until following the deenergization of slow release relay 33, which 70 also remains energized until an interval after the entire series of impulses have been transmitted to the rotary magnet 42. Relay 34 at its armature 57 and its working contact connects the test wiper 75 into electrical 75 connection with the winding of test relay 32. Relay 33 at its armature 56, completes a circuit around armature 48 and its resting contact so as to avoid the impulsive circuit being interrupted should the test 80 relay be operated while wiper 75 is passing over busy or grounded test contacts.

Assuming that the desired line is busy at the present time, there will be a ground potential present upon the test control 101 engaged by the test wiper 75 and the test relay 32 will be energized. Relay 32 upon operating at its armature 52 prepares a locking circuit for itself which is completed upon the deenergization of slow acting relay 34, 90 and at its armature 73 places a busy tone 95 on the lower heavy talking conductor whereby the calling subscriber is notified that the desired line is busy. The calling subscriber will accordingly replace his receiver upon 100 the switchhook thereby initiating the release of the operated switches.

It will now be assumed that the line of the desired substation is one of a group of trunk lines listed under the same directory number, for instance, it may be assumed that the last two digits of which is 21. In this case the circuits of the connector E must be slightly changed in order to enable it to select the first idle one of these lines. This is 110 accomplished in the usual manner by connecting the test contacts 92 and 93, similar to test contacts 101 and 102, together on all except the last line of the group. Under these 115 conditions when a line becomes busy, ground is present upon both these test contacts. As shown the test contacts 92 and 93 and the three subsequent sets of test contacts are so connected. Now, if it is assumed that the first trunk was busy when connection was 120 attempted, the test relay 32 will become energized as before described and will operate and prepare a locking circuit for itself at its armature 52 as before, and in addition, since contacts 92 and 93 are tied together, at its 125 armature 51 prepares an operating circuit for stepping relay 31 which is completed immediately upon the restoration of relay 33. This circuit for stepping relay 31 extends 130 by way of grounded wiper 74, resting con-

tact and armature 68, working contact and armature 58, armature 51 and its working contact, resting contact and armature 54, interrupter springs of rotary magnet 42 and the winding of relay 31 to battery. Relay 31 upon operating at its armature 45 and its working contact completes a locking circuit for itself, and at armature 46 and its working contact prepares a locking circuit for slow release relay 34 which will be completed immediately upon the restoration of slow release relay 33. A branch of the circuit for relay 34 also includes a new circuit for the rotary magnet 42 extending from the grounded spring controlled by armature 53, working contact and armature 46, armature 62 and its resting contact and the winding of rotary magnet 42 to battery. Upon completion of this circuit rotary magnet 42 becomes energized and at its interrupter springs opens the circuit of stepping relay 31, which, upon energizing at its armature 46, opens the circuit of rotary magnet 42, causing this magnet to deenergize. The alternate operation of stepping relay 31 and rotary magnet 42 now continues to take place as long as grounded test contacts 92 are engaged.

If all of the lines of the group are busy, since the last test contact set similar to 92 and 93 are not tied together, there will be no ground potential present on the test contact engaged by the test wiper 74. The test relay 32 will, therefore, be the only relay operated and no further rotary movement can take place, instead the busy tone will be given to the calling subscriber in the same manner as was described in the case where a subscriber's line was called.

It will now be assumed that the first line of the group was idle when connection was attempted therewith by the connector E. Under these circumstances there will be no ground potential present upon test contact engaged by wiper 75 and, therefore, no circuit is completed for test relay 32, or stepping relay 31. Accordingly, following deenergization of slow release relay 34, a circuit is completed extending from grounded working contact and armature 39, armature 52 and its resting contact, upper winding of switching relay 35, resting contact and armature 57, armature 69 and its resting contact, test wiper 75 to battery supplied through the winding of the motor magnet of the incoming individual line switch associated with the line for extending connections to the branch exchange. Relay 35, upon energizing, at its armature 65 and its working contact completes a locking circuit for itself by way of armature 38 and its grounded working contact, opens a point in the operating circuit of wiper switching relay 36 at its armature 66, at its armature 64 opens a point in the operating circuit of busy relay 32, at its armature 63 and its working contact connects direct ground to the private wiper 75 to render the line busy to other subscribers, at its armature 60 and 60' connects interrupted generator and ground, respectively, to the line conductors by way of wipers 78 and 79, at armature 62 opens a point in the operating circuit of rotary magnet 42 and at armature 61 cuts in a low capacity condenser in the upper conductor so that the calling subscriber may hear the signaling operation take place.

When the called subscriber or attendant operator of the private branch exchange answers, a circuit for the ring cutoff relay 30 is completed over the called loop. Relay 30, upon energizing, establishes a locking circuit for itself at its armature 43 in multiple with that described for the switching relay 35 and at its armature 44 and 47 cuts off generator and ground, respectively, from the conductors of the calling line and connects these conductors through to finally complete the talking connection. The back bridge relay 27 is immediately energized over the line of the substation or attendant operator's equipment and supplies talking current to the called subscriber, and at its armature 108 and working contact connects ground to the holding conductor 105 so as to maintain the connector E operated as long as either the calling or called line has his receiver off the hook.

We will now assume that connection is desired with a private branch exchange over any of twenty trunks available to the connector E, or similar switches, but before proceeding with this description it is considered advisable to briefly explain the manner in which the switch is arranged to accomplish this result without increasing its capacity. In illustrating the invention it will be assumed that the particular branch exchange in question has been given the desirable directory number of 5000 and, therefore, when the first digit 0 is transmitted to the connector the wipers 74 to 81, inclusive, will be elevated ten steps. The wiper 76-77, and 80-81 are located six steps or levels below the respective wipers 74-75 and 78-79 so that when digit 0 is dialed and the wipers 74-75 and 78-79 are opposite the 0 or tenth level of the bank contacts, wipers 76-77 and 80-81 are opposite the fourth level of bank contacts. From this it will be appreciated that the twenty trunks available in the present instance are the 10 located in the tenth level and the 10 located in the fourth level of the switch E. Since the number of rotary steps or the number of trunks in any one level is limited to ten, the tenth bank contact in each instance that is, in the 0 level and in the fourth level, are not multiplied. The remaining private contacts of the entire group are multiplied or joined together in

the same manner as was explained in connection with trunk groups of less than ten. Connected with each test contact of the 0 level, such as that corresponding to 93 of 5 the 0 level, are chain relays and the circuits are so arranged, as will subsequently be described, that if, when the switch is elevated to the 0 level, all trunks in that level are busy, the conductor 86 will be grounded, 10 normal post spring 50 will be closed and a circuit will be completed for wiper switching relay 36. This relay will then be locked up and trunk selection will take place on 15 the fourth level in the same manner as if there were only ten trunks available to the branch exchange.

The operations which take place in the selection of a trunk of a large group, as briefly described in the foregoing will now 20 be described in detail. The connector E is seized in the previously described manner and the switch operated responsive to the transmission of the digit 0 to step its associated wiper sets to the tenth and fourth 25 level, respectively. The switch upon taking its tenth step operates shaft springs 50, 55, and 70. The closure of the springs 50 prepares a point in the circuit of wiper switching relay 36, the opening of springs 55 opens 30 the low resistance path to the lower winding of slow release relay 33, while the springs 70 prepare a point in a new operating circuit for stepping relay 31.

Upon the next and final digit 0, being 35 transmitted to the connector E, relays 33 and 34 operate in the manner formerly described. Relay 33, however, in this instance, due to the operated condition of normal post springs 55 is energized through its high resistance winding, which prevents the impulses operatively affecting rotary magnet 42. At this time, since normal post springs 70 are also closed, as soon as armature 54 operates, a circuit is completed for the stepping relay 31 by way of grounded armature 63 and its resting contact, normal post springs 70, working contact and armature 54, interrupter springs of rotary magnet 42 and the winding of stepping relay 31 to battery. 45 Shortly following the transmission of the last impulse relay 33 restores and at springs controlled by armature 53 completes the previously described circuit for rotary magnet 42. The operation from this point depends 50 on whether all the trunks in the 0 level are busy or not. If any one trunk is idle no ground will be present on conductor 86, the operation of normal post spring 50 will be without effect and the switch will operate to 55 cause the selection of an idle trunk in the 0 level in the same manner as described when trunk selection took place in the second level.

If, however, all the trunks of the 0 level 60 are in use, the conductor 86 will be grounded

by the chain relays 111-120 and as a result of the closure of normal post springs 50, a circuit will be completed by way of armature 49 and its back contact, back contact and armature 66, and springs controlled by armature 71 for the wiper switching relay 36, which will immediately operate. Relay 36 at its armature 71 completes a locking circuit for itself and at armature 67, 68, 69, and 72 switches the various conductors of 75 the switch E from connection with the wipers normally used to the auxiliary wipers 76-77 and 80-81, which as previously explained are opposite the fourth level of their respective banks. The trunk selecting operation is not changed by the switching of the wipers and takes place in the same manner as described in the foregoing.

It will be assumed that the twentieth trunk, the tenth trunk of the fourth level, 85 is the only trunk idle. When the wipers 76 and 77 reach the test contacts with which this trunk is associated, no ground being present on test contact 121, busy relay 32 will not be energized, but following the de-energization of slow release relay 34 the 90 previously described circuit for switching relay 35 will be completed resulting in the connection being completed in the manner 95 previously described.

When the conversation is terminated both the subscribers will replace the receivers upon their respective switchhooks. When the receiver is replaced at substation A, the circuit for line relay 26 and slow release 100 relay 28 will be opened. The deenergization of relay 28 causes the calling subscriber's line switch and any intervening selector switches to be restored to normal and also causes ground to be removed from one point 105 of conductor 105, to prepare the circuit for release magnet 122. The switch E is not released, however, until both parties have restored their receivers owing to the fact that the release magnet circuit is still open at 110 armature 109 of the back bridge, relay 27, and the holding conductor 105 for the various relays of the switch E is maintained grounded by armature 108 and its working contact. When the called subscriber replaces 115 his receiver the back bridge relay, however, restores to normal causing the release magnet circuit to be completed and the holding circuit for relays 30, 36, and 35 to be opened, these relays and the switch E accordingly 120 restore to normal, rendering the trunk available for further calls.

In the foregoing description it was assumed that the entire maximum of twenty trunks were utilized as a single group. In 125 many cases a smaller number of trunks are sufficient. For instance, in the case illustrated there might have been only the first five trunks available to the auxiliary wiper set in the fourth level, the remaining five 130

contact sets being utilized as another trunk group accessible to the regular wiper set. Furthermore, if the regular wiper set has provided below it auxiliary wipers located five steps below them instead of six, as illustrated, the switch may be utilized to connect with any of five groups of over ten trunks each and also be able to select any one of five or more groups comprising less than ten trunks, in which case it will be understood that the small trunk groups would be located in the righthand portion of the five lower bank contact sets and be selectable only by the regular wiper set. In such an arrangement the normal post springs 50, 55, and 70, instead of operating on the 0 level only, would operate on the sixth to tenth or 0 level inclusive.

From the foregoing it will be appreciated that applicant has designed a rotary connector having features highly desirable in certain instances over former switches of this type.

What is claimed is:

25 1. In a telephone system, a connector switch having two sets of wipers, a plurality of levels of bank contacts accessible to said wiper sets, means for directly operating said switch to cause each of said wiper sets 30 to be positioned opposite a different level of bank contacts, means for causing said wipers to successively engage all the contacts in the level opposite which they have been positioned, lines terminating in said bank contacts, means for making said lines busy, means normally causing only one set of wipers to test for an idle line as it successively engages its bank contacts, and means 35 for causing only the other wiper set to test if all lines available to the first wiper are busy.

2. In a telephone system, a connector having two sets of wipers, lines divided into groups and subgroups accessible to one of said wiper sets only, and other lines divided 45 into groups and subgroups accessible to both wiper sets, means for directly operating said connector in a primary direction to select a group of lines available to one of said wiper sets, and means effective in case all lines in said group are busy for rendering the other wiper set available to select an idle line of a second group.

3. In a telephone system, an automatic 50 switch of the two directional type, a plurality of wiper sets, a bank of contacts divided into a plurality of groups, lines terminating at said contacts, directive controlled means for elevating one of said wiper sets opposite one group of said contacts and for simultaneously moving the other wiper set opposite a second group of contacts, means 55 for causing said switch to move both wiper sets to select an idle line of a group and automatic means effective after the directive movement for determining which wiper set will be used.

and prior to the selecting movement for determining which wiper set will be used.

4. In a telephone system, a connector switch, groups of lines accessible to said connector switch, means for directly operating said switch to select two groups of said lines, means for causing said switch to automatically test for an idle trunk in one of said groups responsive to any digit impulse or impulses transmitted to it, and means effective only in case all trunks in one group are busy for causing the lines in the other group to be tested.

5. In a telephone system, a rotary connector switch, lines accessible to said switch, 80 said switch responsive to a series of impulses to cause the selection of a particular group of said lines, means subsequently responsive to only one impulse of a subsequent impulse series to cause one of the lines of the selected group to be connected with irrespective of the busy or idle condition of the first lines in the selected group and means in said switch for absorbing the remaining impulses of the last impulse series. 90

6. In a telephone system a connector switch, groups of lines terminating in bank contacts of said switch, said switch responsive to one or more series of impulses to select a group of lines and means automatically responsive to cause the switch to select an idle line of the selected group where the selected group requires more than one series of impulses and responsive to an impulse of a second impulse series irrespective of the number of impulses in the latter series to cause the switch to select an idle line of a group selected by one impulse series. 100

7. In a telephone system, an automatic switch having normally effective and normally ineffective wiper sets respectively, a plurality of levels of contacts each level having contacts accessible to only one of said wiper sets, other levels of contacts each having a contact available to both wiper sets and means for reversing the status of said wiper sets automatically after the selection of the level. 105

8. In a telephone system, an automatic switch of the two directional type, a plurality of wiper sets, lines terminating at said contacts, directive controlled means for elevating one of said wiper sets opposite one group of said contacts and for simultaneously moving the other wiper set opposite a second group of contacts, means for causing said switch to move both wiper sets to select an idle line of a group and automatic means effective after the directive movement for determining which wiper set will be used. 115

9. In a telephone system, an automatic switch of the two directional type, a plurality of wiper sets, a bank of contacts divided into a plurality of groups, lines terminating at that contact, directive con- 120 125

trolled means for elevating one of said wiper sets opposite one group of said contacts and for simultaneously moving the other wiper set opposite a second group of contacts, means for causing said switch to move both wiper sets to select an idle line of a group, and automatic means effective independent

of said directive controlled means for determining which wiper set will be used.

In witness whereof, I hereunto subscribe my name this 31st day of August, A. D., 1925.

RUDOLPH F. STEHLIK.

trolled means for elevating one of said wiper sets opposite one group of said contacts and for simultaneously moving the other wiper set opposite a second group of contacts, means for causing said switch to move both wiper sets to select an idle line of a group, and automatic means effective independent

of said directive controlled means for determining which wiper set will be used. In witness whereof, I hereunto subscribe ¹⁰ my name this 31st day of August, A. D., 1925.

RUDOLPH F. STEHLIK.

CERTIFICATE OF CORRECTION.

Patent No. 1,638,513.

Granted August 9, 1927, to

RUDOLPH F. STEHLIK.

It is hereby certified that error appears in the printed specification of the above numbered patent requiring correction as follows: Page 5, strike out lines 114 to 130, and page 6, lines 1 to 9, comprising claims 8 and 9, and insert the following as claims 8 and 9:-

8. In a telephone system, an automatic switch having two wiper sets, means for moving said wiper sets simultaneously, a plurality of levels of contacts available to both wiper sets but available to one wiper set before any level becomes available to the other wiper set, and another plurality of levels of contacts available only to one of said wiper sets.

9. In a telephone system, a connector switch, groups of lines terminating in bank contacts of said switch, said switch responsive to one or more series of impulses to select a group of lines, means automatically effective after a group has been selected by more than one series of impulses for causing it to automatically initiate its line selecting movement, means for preventing the initiation of the line selecting movement where the group is selected by one impulse series, and impulse controlled means for causing the line selecting movement to be initiated in the latter instance.;

and that the said Letters Patent should be read with this correction therein that the same may conform to the record of the case in the Patent Office.

Signed and sealed this 19th day of June, A. D. 1928.
